UNITED STATES PATENT OFFICE.

DAVID W. R. MORGAN, OF SWARTHMORE, PENNSYLVANIA, ASSIGNOR TO WESTINGHOUSE ELECTRIC AND MANUFACTURING COMPANY, A CORPORATION OF PENNSYLVANIA.

SURFACE CONDENSER.

Application filed June 3, 1921. Serial No. 474,853.

My invention relates to surface condensers and more particularly to horizontal tube condensers of the radial flow type, and it has for an object the provision of apparatus which 5 shall economically and efficiently maintain a high vacuum within a surface condenser under all operating conditions, and which shall effect a gradual reduction in the volume of the non-condensable gases in the fluid treated and deliver these gases to a removal mechanism at a temperature and specific volume approximating that corresponding to the temperature at which cooling water is delivered to the condenser.

It is a further object of my invention to provide a condenser in which the constituent parts shall be so constructed and arranged that the cooling tubes may be cleaned in sections without closing down the power device served by the condenser and without materially interfering with the effectiveness of the condenser. These and other objects and advantages of my invention, which will be more manifest in the further description 20 thereof, may be attained by an apparatus hereinafter described and illustrated in the accompanying drawing, in which—

Fig. 1 is a longitudinal sectional view of a condenser embodying my invention; Fig. 2 is a transverse sectional view taken on line 2—2 of Fig. 1; Fig. 3 is a transverse sectional view taken on line 3—3 of Fig. 1; Fig. 4 is a transverse sectional view of one of the water boxes of my improved condenser taken 25 on line 4—4 of Fig. 1; Fig. 5 is a transverse sectional view of the other water box taken on line 5—5 of Fig. 1; Fig. 6 is a transverse sectional view of a modified form of the water box illustrated in Fig. 4; and Fig. 7 is a transverse sectional view of a modified 30 form of the water box illustrated in Fig. 5.

In steam power plants employing turbines as prime-movers, the best efficiency is obtained when the pressures in the exhaust 45 passage of the turbine are maintained at low absolute values. Condensers are commonly designed to produce vacua of 28 and 29 inches, referred to a 30 inch barometer. Under these high vacua conditions, the non-condensable gases and uncondensed vapors in condensers assume large specific volumes. Since the energy required to remove the non-condensable gases and the uncondensed vapors, hereinafter for brevity and distinction 50 called air, from the condenser is approxi-

mately proportional to the actual volume of the air necessary to be handled by the air withdrawal mechanism, good efficiency in the operation of the air-withdrawal mechanism demands that the specific volume of the air 60 be reduced to a minimum prior to its delivery to the withdrawal mechanism.

It is furthermore desirable in power installations employing surface condensers of the water tube type to provide means for 65 cleaning the water tubes of the condenser and at the same time to maintain a requisite vacuum within the condenser so that it will be unnecessary to withdraw the condenser from service or to reduce materially the effectiveness of the unit during the cleaning 70 period.

The apparatus embodying my invention and herein described is so constructed as to produce with a high degree of efficiency a 75 suitable vacuum within a condenser both under normal operating conditions and during periods in which the tubes are being cleaned. This is accomplished by providing in a surface condenser means for utilizing a 80 part of the nest of cooling tubes for preliminarily reducing the temperature and the specific volume of the air being withdrawn, then causing a further reduction in the temperature and the specific volume thereof by 85 surrounding at least a portion of air-off-take conduits within the condenser by water jackets, the water being delivered thereto from the cooling water supply and discharged therefrom into a second pass of the 90 condenser. This arrangement effectually minimizes the transfer of heat from the steam and condensate within the condenser to the air being withdrawn and at the same time reduces the air temperature and specific 95 volume to approximately that corresponding to the temperature of the cooling water delivered to the condenser.

Provision is made for the cleaning of the condenser tubes without destroying the 100 vacuum within the condenser in the following manner. Vertical partitions within the water boxes cooperate with the cooling tubes to divide the condenser into a number of vertical compartments, through each of which cooling water flows in parallel, separated streams. Water may be shut off and withdrawn from any one of these vertical compartments for the purpose of cleaning the 105 tubes thereof, the other compartments func- 110

tioning normally to effect the condensation of the steam entering the condenser. The air-cooling and withdrawing apparatus cooperates in a particularly advantageous manner during the cleaning period. The air-offtake is located centrally within the tube nest and, due to this position, produces an efficient flow of gases and vapor through the cooling tubes, irrespective of the location of the section of tubes being cleaned. The water jackets surrounding the withdrawal conduits are supplied with water independently of any of the vertical compartments so that the air being withdrawn is always subjected to a further cooling action prior to its delivery to the withdrawal mechanism. This arrangement insures an efficient action of the air-withdrawal mechanism and maintains a satisfactory vacuum within the condenser during periods of cleaning.

For a more detailed understanding of an apparatus embodying my invention, reference may be had to the drawing in which I have indicated a condenser at 10 comprising a shell 11, which has end portions 12, 13 of reduced diameter. An inlet 14 for exhaust steam or other medium to be condensed, is provided in the upper portion of the shell 11. As is customary, water boxes 14, 15 are bolted or otherwise secured to the end portions 12, 13 of the shell 11, tube plates 16, 17 being held between the flanges on the water boxes 14, 15 and cooperating flanges on the end portions 12, 13 of the condenser shell. Tubes 18 are secured in the tube plates 16, 17, so as to traverse the space within the shell 11, and to open into the water boxes 14, 15, in the usual manner. As shown, the tubes and water boxes are arranged to effect a two-pass flow of cooling water through the condenser, although it is to be understood that a single pass or multi-pass flow of cooling water may be utilized if desired.

The nest of tubes 18 and tube plates 16, 17 are disposed eccentrically with respect to the cylindrical lower portion of the condenser shell, the tube nest being nearest the shell at the lowermost portion thereof. This arrangement provides adequate passages 19, 20 of decreasing flow area in open communication with the steam inlet 14 and extending downwardly between the longitudinally extending walls of the condenser shell and the tube nest in such a manner that the steam or other fluid being condensed can enter the tube nest at substantially any point throughout its perimeter. In the lower portion of the shell 11 is a hot-well 21 provided with an outlet port 22 through which the condensate may be removed.

An air cooling chamber 25, which may be of any suitable size and conformation, is disposed within a central upper zone of the tube bank and, as illustrated, is a rectangular chamber having two vertically disposed side

walls 26, 27 extending the full length of the condenser shell and preferably secured to and supported by the tube plates 16, 17. A portion of the second pass cooling tubes traverse the cooling chamber 25 for a purpose hereinafter more fully set forth. A roof member 28 secured to the side-wall members 26, 27 forms the top or roof of the chamber 25. An additional roof member 29 spaced from the member 28 may be provided to prevent the incoming steam from impinging against the roof member 28 and from heating the air passing through the cooling chamber 25.

Extending upwardly through the open bottom of the air-cooling chamber 25 is an air-withdrawal chamber 30 which comprises two longitudinally extending plates 31, 32 extending the full length of the condenser. Conduits 34 extend downwardly from and communicate with the chamber 30, the bottom of which is closed except for the ports communicating with the conduits 34. The conduits 34 lead downwardly through the bottom of the condenser and discharge into an air-withdrawal manifold 35. The conduits 34 are surrounded by jackets 38, spaced from the conduits to form water-containing chambers. Water is supplied to the jackets 38 from a cooling water main 39 by means of a pipe 40 and branches 41, the latter being provided with valves 42 to control the flow of water through the several jackets. Discharge pipes 43 are arranged to carry away the water from the upper portions of the water jackets 38 into the water boxes.

The cooling water passages are divided into a number of vertically separated sections for the purpose of facilitating the cleaning of the cooling tubes. Access to the cooling tubes 18 for the purpose of cleaning the tubes is had through clean-out openings 45 disposed in the outer walls of the water boxes 14 and 15. Cover plates 46 are provided to close the openings and are held in place in any well-known manner. Each section of both of the water boxes 14 and 15 is provided with these clean-out openings so that access may be to the tube plates and to the tubes from either end of the condenser. The arrangement is such that while one section is being cleaned, the other section or sections function to effect the condensation of the steam entering the condenser. Any suitable number of separated sections may be provided in a condenser depending upon the character of duty the condenser is called upon to perform. In condensers which carry a uniform load continuously for long periods of time, a larger number of separated cooling sections is preferable. The cooling sections may be of the single-pass, two-pass or multi-pass type. As illustrated in Figures 4 and 5, the condenser is provided with two cooling water sections, 139

each consisting of two passes. In carrying out this distribution of the cooling water through the condenser, I provide in the water box 15 a vertical partition 50 and 5 a horizontal partition 51, which divide the box into four chambers 52, 53, 54 and 55. Cooling water is admitted to the two lower chambers 54, 55 from the manifold 39 through branch pipes 56, 57, each of which 10 is preferably provided with a shutoff valve 58, 59. The upper water chambers 52, 53 are also provided with outlet connections 60, 61 which lead to any suitable discharge means. The water box 14 is provided with 15 a single vertical partition 65 which divides the water box into two water compartments 66, 67, and which cooperates with the partition 50 of the water box 15 to form the separated cooling water sections. Drainage pipes 68 having valves 69 may also be 20 provided.

Having described the arrangement of apparatus embodying my invention, the operation thereof is as follows. Steam from a 25 turbine, or other steam consumer, is admitted to the condenser through the inlet 14, and passes downwardly through the condenser so as to surround the nest of tubes 18, which as above described, are arranged 30 eccentrically within the condenser shell. The steam enters substantially throughout the entire periphery of the tube nest and passes radially therethrough toward the inlet passages of the air-cooling chamber 25. 35 The steam traverses in relatively short paths through the tube nest, the condenser being preferably so designed that the condensable vapors are largely separated from the non-condensable gases prior to the entrance of 40 the air into the inlet of the air-cooling chamber 25. The air passes upwardly through the chamber 25 contacting with the second pass tubes 18 therein which serve to separate out the condensable vapors and to reduce the temperature and specific volume 45 of the air, the condensate therefrom draining back into the condenser. The cooled air then passes into the open upper end of the withdrawal chamber 30 and downwardly 50 therethrough into the withdrawal conduit 34. Since the chamber 30 is surrounded by cooling tubes 18, a further reduction in the temperature and the volume of the air takes 55 place during its passage therethrough. The conduits 34 are rectangular in cross-section and afford an extended contact-cooling surface for the air passing therethrough, the water jacket 38 surrounding the conduits 34 maintaining the conduit walls at a relatively 60 low temperature. The water for the jacket 38 may preferably be taken from the cooling water inlet manifold 39 through pipe 40 and branches 41, the quantity flowing therethrough being regulated by valves 42. 65 It will thus be seen from the above descrip-

tion that the air is progressively cooled, first in the chamber 25, then in the chamber 30 and finally within the conduits 34, the cooling agencies being progressively of lower temperatures throughout the travel of the 70 air being removed.

In cleaning the condenser, the valve in one of the branch inlets, for example the valve 58 in the branch 56 is closed and the water drained from the vertical compartment comprising chambers 52, 54, 67, and associated tubes 18, in any suitable manner, as through the pipe 68 and valve 69. Access may then be had to the tubes entering the chambers 52, 54 and 67 and the tubes 80 cleaned by means of any suitable cleaning instrument. During this operation, the tubes being cleaned are inactive to condense steam. The cooling tubes communicating with the chambers 53, 55 and 66 are, however, functioning normally to condense the steam entering the condenser and are able to maintain a satisfactory vacuum within the condenser, particularly if the power plant is operating under a light load. The 90 air passing through the chambers 25, 30 and conduit 34 is sufficiently reduced in volume so that the air withdrawal means operates at nearly normal efficiency and is enabled to maintain a suitable degree of 95 vacuum within the condenser. It will be noted that while the tubes on either side of the condenser are being cleaned, the tubes on the other side of the condenser are so disposed with relation to the air-offtake 100 means that a direct and positive flow of steam through the active condensing portions of the tube nest is effected.

In Figs. 6 and 7 of the drawings, the water box 15' is shown provided with three 105 vertically extending partitions 70, 71 and 72 and a single horizontal partition 73. Co-operating partitions 74, 75 and 76 in the water box 14' are also provided. An inlet manifold 39' provided with four branch 110 connections 78, 79, 80 and 81, each provided with valve 82, is arranged to supply the several lower chambers of the water box 15' with cooling water in a manner similar to that described with relation to Fig. 4. Discharge connections 83, 84, 85 and 86 leading from the upper chambers of the water box 15' are also provided.

The operation of my condenser when provided with the multi-chamber water boxes 115 14', 15' illustrated in Figs. 6 and 7, is identical with that described above in relation to Figs. 1 to 5, inclusive. The division of the cooling water flowing through the condenser into a number of separated streams 120 permits the cleaning of the condenser tube while the power plant is operating under normal load without materially reducing the over-all efficiency of the plant.

It is to be understood that the air-cooling 125

- and removal apparatus illustrated and described above may be utilized to full advantage in a condenser in which there is a single or multi-pass flow of cooling water 5 through the condenser and that the arrangement for effecting low temperatures and low specific volumes of the air withdrawn is in no wise limited to condensers having a plurality of separated cooling water sections. 10 It is evident, however, that the arrangement within the condenser of the specific air cooling construction, herein described, cooperates with the separated cooling water sections in such a manner as to avoid a 15 duplication of air-cooling and air withdrawal mechanism, and to secure satisfactory condenser conditions both during periods of normal operation and during cleaning periods. 20 While I have shown my invention in but two forms, it will be obvious to those skilled in the art that it is not so limited but is susceptible of various other changes and modifications, without departing from the spirit 25 thereof, and I desire, therefore, that only such limitations shall be placed thereupon as are imposed by the prior art or as are specifically set forth in the appended claims.
- What I claim is:—
- 30 1. The combination in a condenser having a shell defining a condensing chamber and a nest of cooling tubes traversing the chamber, of partitions defining within the condensing chamber a non-condensable gas 35 cooling chamber, said cooling chamber embracing cooling tubes in the upper central portion of the tube nest and being open at the bottom for the admission of non-condensable gases thereto from the central portion 40 of the tube nest, and means for withdrawing the non-condensable gases from the upper portion of the chamber downwardly therethrough and without the condenser.
2. The combination in a condenser having 45 a shell defining a condensing chamber, and a nest of cooling tubes traversing the chamber, of partitions defining within the condensing chamber a non-condensable gas cooling chamber, said cooling chamber embracing cooling tubes in the central upper portion of the tube nest and being open at the bottom for the admission of non-condensable gases thereto from the central portion 50 of the tube nest, and means for withdrawing non-condensable gases from the upper portion of the chamber downwardly therethrough, and means within the condenser for further cooling the non-condensable gases during their passage through 55 said withdrawal means.
3. The combination in a condenser having a shell defining a condensing chamber, and a nest of cooling tubes traversing the chamber, of partitions defining within the condensing chamber a non-condensable gas 60 cooling chamber, said cooling chamber embracing cooling tubes in an upper portion of a central vertical zone of the tube nest and being open at the bottom for the admission of non-condensable gases thereto, an open-topped outlet channel extending centrally of the said cooling chamber, the open top communicating with the upper portion thereof, and an outlet duct communicating with a lower portion of said channel and leading outwardly through the condenser shell.
- 65

cooling chamber, said cooling chamber embracing cooling tubes in the central upper portion of the tube nest and being open at the bottom for the admission of non-condensable gases thereto from the central portion of the tube nest, and means for withdrawing non-condensable gases from the upper portion of the chamber downwardly therethrough, and means within the condenser for further cooling the non-condensable gases during their passage through said withdrawal means, comprising a water jacket surrounding at least a portion of the said withdrawal means. 70

4. The combination in a condenser having a shell defining a condensing chamber, and a nest of cooling tubes traversing the chamber, of a non-condensable gas cooling chamber within the tube nest and traversed by a portion of the cooling tubes, said gas cooling chamber having inlet means situated well within the tube nest, means for withdrawing non-condensable gases from portions of the gas cooling chamber remote from the inlet means, said withdrawal means traversing the gas cooling chamber and extending through the condenser shell, and means within the condenser for further cooling the non-condensable gases during their passage through said withdrawal means, comprising a water jacket surrounding at least a portion of the said withdrawal means. 80

5. The combination in a condenser comprising a shell defining a condensing chamber and having a vapor inlet means and a condensate outlet means, and a nest of cooling tubes traversing the chamber, of partition walls extending the length of the condensing chamber and defining therein a non-condensable gas cooling chamber, said cooling chamber embracing cooling tubes in an upper portion of a central vertical zone of the tube nest and being open at the bottom for the admission of non-condensable gases thereto, an open-topped outlet channel extending centrally of the said cooling chamber, the open top communicating with the upper portion thereof, and an outlet duct communicating with a lower portion of said channel and leading outwardly through the condenser shell. 90

6. The combination in a condenser comprising a shell defining a condensing chamber and having a vapor inlet means and a condensate outlet means, and a nest of cooling tubes traversing the chamber, of partition walls extending the length of the condensing chamber and defining therein a non-condensable gas cooling chamber, said cooling chamber embracing cooling tubes in an upper portion of a central vertical zone of the tube nest and being open at the bottom for the admission of non-condensable gases thereto, an open-topped outlet channel ex- 100

105

110

115

120

125

130

tending centrally of the said cooling chamber, the open top communicating with the upper portion thereof, and an outlet duct communicating with a lower portion of said channel and leading outwardly through the condenser shell, and means for reducing the temperature and specific volume of the non-condensable gases passing through said outlet duct including a water jacket surrounding the said duct.

7. The combination in a condenser comprising a shell defining a condensing chamber and having a vapor inlet means, a condensate discharge means, cooling water boxes on the ends of the shell and a nest of tubes traversing the condensing chamber and communicating with said water boxes, of means associated with the water boxes for causing cooling water to pass through the condenser in a plurality of separated zones, means for shutting off the flow of water through any zone, and means for withdrawing non-condensable gases from a central portion of the tube nest, whereby a minimum reduction in vacuum within the condenser results from the shutting off of the flow of water through any zone.

8. The combination in a condenser comprising a shell defining a condensing chamber and having a vapor inlet means, a condensate discharge means, cooling water boxes on the ends of the shell and a nest of tubes traversing the condensing chamber and communicating with said water boxes, of means associated with the water boxes for causing cooling water to pass through the condenser in a plurality of separated zones, means for shutting off the flow of water through any zone, and means for withdrawing non-condensable gases from a central portion of the tube nest, and means within the condenser for cooling the said gases during their withdrawal from the condenser, whereby when any of the separated zones is withdrawn from service for purpose of cleaning the tubes thereof, a minimum decreased efficiency in the operation of the condenser results.

9. The combination in a condenser comprising a shell defining a condensing chamber, cooling water boxes on the ends of the shell and a nest of cooling water tubes traversing the condensing chamber and communicating with said water boxes, of a vertical partition in each water box cooperating with the cooling tubes to form a plurality of separated zones for the passage of cooling water through the condenser, a central horizontal partition wall in one of the water boxes serving to provide with the vertical partition therein a plurality of lower intake cooling water chambers and a plurality of upper outlet cooling water chambers, conduits communicating with each of the said cooling water chambers, partition walls de-

fining within the condensing chamber a non-condensable gas cooling chamber, said cooling chamber embracing cooling tubes in the central upper portion of the tube nest and being open at the bottom for the admission of air thereto, and means for withdrawing the non-condensable gases from the upper portion of the chamber, whereby when any of the separated zones is withdrawn from service for purposes of cleaning the tubes thereof a minimum decreased efficiency in the operation of the condenser results.

10. The combination in a condenser comprising a shell defining a condensing chamber, cooling water boxes on the ends of the shell and a nest of cooling water tubes traversing the condensing chamber and communicating with said water boxes, of partitions defining within the condensing chamber, a non-condensable gas cooling chamber, said cooling chamber embracing cooling tubes in the central upper portion of the tube nest and being open at the bottom for the admission of air thereto, means for withdrawing non-condensable gases from the upper portion of the chamber, means within the condenser for further cooling the non-condensable gases during their passage through said withdrawal means, comprising a water jacket surrounding at least a portion of said withdrawal means, a conduit supplying cooling water to one of said water boxes, and means for supplying water to the jacket from the conduit and discharging the water from the jacket to one of the water boxes.

11. The combination in a condenser comprising a shell, defining a condensing chamber, cooling water boxes on the ends of the shell and a nest of cooling water tubes traversing the condensing chamber and communicating with said water boxes, of partition walls extending the length of the condensing chamber and defining therein a non-condensable gas cooling chamber, said cooling chamber embracing cooling tubes in an upper portion of a central vertical zone of the tube nest and being open at the bottom for the admission of non-condensable gases thereto, an open-topped outlet channel extending centrally of the said cooling chamber, the open top communicating with the upper portions of the cooling chamber, and outlet duct communicating with a lower portion of said channel and leading outwardly through the condenser shell, means for reducing the temperature and specific volume of the non-condensable gases passing through the said outlet duct including a water jacket surrounding the said duct, and means for supplying cooling water to the jacket and discharging the water from the jacket into one of the water boxes.

12. The combination with a condenser having a shell defining a condensing cham-

- ber and a nest of cooling tubes traversing the chamber, of means for admitting cooling water to one portion of the shell, means for discharging cooling water from another portion of the shell, the cooling water being gradually heated in its passage through the shell, means for removing air and non-condensable gases from a portion of the shell through which relatively warm cooling water passes, and means for conveying the air and non-condensable gases through a portion of the shell through which relatively cold cooling water passes, whereby the air and non-condensable gases are effectively cooled prior to their removal from the condenser shell.
13. The combination with a condenser having a shell defining a condensing chamber and a nest of cooling tubes traversing the chamber, of means for admitting cooling

water to one portion of the shell, means for discharging cooling water from another portion of the shell, the cooling water being gradually heated in its passage through the shell, means disposed within the shell for removing the air and non-condensable gases, said removal means embracing cooling tubes through which relatively warm cooling water passes, whereby the air and non-condensable gases are partly cooled, and means for conveying the air and non-condensable gases through that portion of the shell in which the tubes convey relatively cold cooling water, whereby the air and non-condensable gases are further cooled prior to their removal from the condenser shell.

In testimony whereof, I have hereunto subscribed my name this 27th day of May, 1921.

D. W. R. MORGAN.
